UNITED STATES PATENT OFFICE.

JOHN J. WHEAT, OF INDIANAPOLIS, INDIANA, ASSIGNOR OF THREE-FOURTHS
TO NATHAN M. NEED, THOMAS F. THORNE, AND FREDERICK H. KIL-
BOURN, OF CHICAGO, ILLINOIS.

TRACK-CLEANER.

SPECIFICATION forming part of Letters Patent No. 443,247, dated December 28, 1890.

Application filed August 31, 1885. Renewed May 29, 1890. Serial No. 353,640. (No model.)

To all whom it may concern:

Be it known that I, JOHN J. WHEAT, a citizen of the United States, residing at Indianapolis, in the county of Marion and State of Indiana, have invented certain new and useful Improvements in Track-Cleaners, of which the following is a specification, to wit:

This invention relates to railway-track cleaners; and it consists in certain peculiarities of the construction and arrangement of the same, substantially as will be hereinafter more fully described, and pointed out in the claims.

In order to enable other skilled in the art to which my invention pertains to make and use the same, I will now proceed to describe its construction and operation, referring to the accompanying drawings, in which—

Figure 1 is a longitudinal vertical section 20 of my device applied to a car especially constructed for this purpose. Fig. 2 is a top plan view of the same. Fig. 3 is a side elevation of my invention applied to an ordinary locomotive-engine. Fig. 4 is a front elevation of the device, and Fig. 5 represents the manner of controlling the direction of the discharge pipe.

a represents a car or frame of any desired construction, upon the forward end of which 30 is secured a casing a', in which revolves an exhaust-fan a² of suitable size and form for the purpose in view. The outer side of the casing is cut away to admit the snow or other obstruction, and to this side of the casing 35 is secured a forwardly-projecting gatherer or guide-shell b, which serves to collect the air, snow, &c., and guide or deliver it to the fan. The upper side of the fan-casing a' is formed with an outlet b', on which is placed 40 a discharge pipe or spout b², as shown.

It will be understood that when the fan is rapidly revolved the air is exhausted from in front of the device, and with it the snow, sand, or other obstruction is drawn into the fan and 45 forcibly discharged through the pipe b². In most instances it will be sufficient to throw the snow, &c., off at one side of the track; but in city streets and in passing houses this is not practical, and to enable it to be delivered

close alongside the track, or at any other 50 point desired, I swivel this discharge-pipe and provide suitable means by which the attendant may at will throw the discharge to one side or the other and either at right angles or back alongside the track, as found 55 desirable in use. This may be done in various ways; but I have herein represented the discharge-pipe as provided with small friction-wheels c, which support it and travel upon a flange c' on the casing. The discharge 60 is also provided with a toothed gear c², with which meshes a pinion c³ on a shaft c⁴, which is extended within easy reach of the operator and by means of which he may direct the discharge at will without stopping or in any 65 way interfering with the work.

In cutting into a bank of snow the fan will of course remove and throw off any snow which may be in front of its guide-funnel or gatherer, and a clear track be thus cut; but the 70 snow at the side is liable to slide down upon the track either during or after the passage of the train, and to prevent this I form the sides of the funnel or gatherer and casing for a suitable distance flaring, or wider at the 75 upper than at the lower edge, as at d, and this acts to press back and pack the wall of snow at the side and thus prevent its falling upon the track. The large funnel is carried within a few inches of the track-rails and will remove all snow of any considerable depth and likely to seriously block the passage of the 80 train; but to remove such as may be left upon the rails, or for use in lighter snows, where the larger fan is not needed, I place beneath 85 the large guide-funnel over each rail a hood or auxiliary gatherer or funnel d', which has a horizontal opening, as in Fig. 1. From each of these hoods a pipe d² extends around the large fan, and these two pipes are connected 90 with a smaller exhaust-fan e, which is also provided with an adjustable discharge e', and through these hoods and fans the lighter snows, or residue left by the larger, is drawn off the rails, leaving a perfectly free track 95 for the train.

I do not desire to confine myself to any particular mode of operating these fans. In Fig.

1 I have shown them placed upon a car built
for their reception and operated by direct
connection with an engine of well-known
form. On the fan-shaft I have also shown a
5 belt-pulley and a bevel-gear, either of which
may be used to transmit motion from some
other suitable power and located where de-
sired.

In Fig. 3 I have shown the large fan at-
10 tached to the front of an ordinary engine, such
as are in common use upon railroads, and
though I have here shown an auxiliary engine
for driving this fan I may as well connect it
15 to the main engine, either direct or by gear-
ing or other well-known connection with the
drive-wheels or axles, as may seem most de-
sirable. In this figure I have not shown the
auxiliary fan, as I do not desire to complicate
20 the drawings, and its connection and use in
this case are obvious from an inspection of
Fig. 1. In any case, whether in use with the
car of Fig. 1 or the engine of Fig. 3, I desire
25 to use the flaring casing to press back and
solidify the wall of snow on either side of the
track and thus retain it in place. It is ob-
vious that a car or engine having this ex-
haust-fan in use may be driven forward at
30 fair speed, as the capacity of the fan is
such as to remove the obstruction with suffi-
cient rapidity for such forward motion. It
will be obvious that an exhaust-fan draw-
ing into it the loose particles of snow before
35 they become pressed or packed will easily
and rapidly discharge them through the ad-
justable pipe to any desired location and
without any necessity for ramming or cutting
the mass of snow, which thereby becomes
40 much harder to remove. By reference to the
drawings it will be seen that I form the ad-
justable discharge-pipe in such manner that
it discharges at an upward angle and by this
means am enabled to throw the snow out of a
45 cut or over banks, &c., to any desired point,
and this is important, as were this discharge
tend to place the snow in position to again
fall upon the track and not remove it to the
proper distance for utility.

The suction of the large fan is sufficiently
50 strong to readily draw in all obstructions
which may be within range of its gatherer or
guide-casing, and the residue is entirely re-
moved by the auxiliary suction. This latter
is either in two separate gatherers, as just
55 described, or in one large chamber having an
opening extending clear across the track, and
in this latter case all the snow is removed,
not only from the track-rails, but also be-

tween them and on each side to the full width
of the cross-ties, and I prefer this construc- 60
tion in consequence.

It will be understood that this machine is
operated wholly by pneumatic force. The
fan-blades do not cut the snow from the bank;
but the outer ends of these blades, it will be 65
seen, are covered, thus enabling the fan to
create a vacuum in the flaring casing, by
means of which the outside atmospheric
pressure is made to drive the snow into and
through the fan, and it is discharged entirely 70
by such force and not by the contact with the
fan. To accomplish this it is necessary to
inclose the peripheral outer face of the fan
and extend in front of it a gatherer, as shown.

I do not desire to be confined to the exact 75
shape or angle of the flaring casing, as this
is altered to suit and presses back the upper
part of a bank of snow, so that it will not in-
terfere with or be disturbed by the subse-
quent passage of trains. By thus pressing the 80
snow back at the top by the successive pas-
sage of the cars it will be seen that the snow
is by this incline pressed back substantially
on the arc of a circle struck from or near the
lower edge of the casing. 85

Having thus fully described my invention,
what I claim as new, and desire to secure by
Letters Patent, is—

1. In a railway-track cleaner, an exhaust
hood or chamber having a horizontal open- 90
ing over the track-rail, in combination with
an exhaust-fan connected with said cham-
ber, substantially as and for the purpose set
forth.

2. In a railway-track cleaner, the combi- 95
nation, with a main exhaust-fan provided
with a guide-funnel and a discharge pipe or
opening, of an auxiliary exhaust-fan con-
nected to hoods or chambers suspended im-
mediately over the track-rails, and also pro- 100
vided with a suitable discharge-opening, sub-
stantially as and for the purpose shown and
described.

3. In a railway-track cleaner, an inclosing
frame or case made flaring and wider at its 105
upper edge, the sides inclining inwardly to a
point at or near the rail, whereby the upper
part of a snow-bank is packed, substantially
as and for the purpose set forth.

In testimony whereof I affix my signature in 110
presence of two witnesses.

JOHN J. WHEAT.
